UNITED STATES PATENT OFFICE.

NUNEZ CLARENCE FERRIS, OF BROOKLYN, NEW YORK, ASSIGNOR TO ELIZABETH F. BOYLE, OF BROOKLYN, NEW YORK.

APPARATUS FOR WINDING MUSIC ROLLS.

Application filed May 3, 1920, Serial No. 378,548. Renewed September 22, 1922. Serial No. 589,917.

To all whom it may concern:

Be it known that I, NUNEZ CLARENCE FERRIS, a citizen of the United States, residing in the city of New York, borough of Brooklyn, in the county of Kings and State of New York, have invented a certain new and useful Improvement in Apparatus for Winding Music Rolls, of which the following is a specification.

10 The invention relates to apparatus for spooling music sheets, and the object of the invention is to provide simple, easily operated, power-driven mechanism for rotating simultaneously a plurality of spools and 15 guiding the sheets thereto, with means whereby the operator may turn any of such spools in advance independently of the others in initiating the winding operation or for other purposes.

20 The invention consists in certain novel features of construction and arrangement by which the above and other objects are attained, to be hereinafter described and claimed.

25 The accompanying drawings form a part of this specification and show the invention as it has been carried out in practice.

Figure 1 is a front elevation of the complete winding machine.

30 Figure 2 is a vertical section, partly in elevation, on a larger scale, taken on the line 2—2 in Figure 1, showing the spool operating mechanism.

Figure 3 is a front elevation of one of the 35 driven devices for holding the spool during the winding operation.

Figure 4 is an end view of the same.

Figure 5 is a front elevation of one of the 40 driving sprocket-wheels and its clutch, for rotating the driven device shown in Figures 3 and 4.

Figure 6 is a face view of such driving sprocket-wheel and clutch.

Similar letters of reference indicate the 45 same parts in all the figures.

A A are uprights or legs supporting a table A' on which is a plate B of sheet metal forming the upper face of the table and having transverse flanges or ribs B' arranged in pairs, spaced to match to a music sheet received between such pairs, and guide such

sheet smoothly across the table to the spool. The table as shown in Figure 1, is equipped for five sheets one of which, at the centre, may be a master-sheet. 55

On the rear of the table is a horizontally disposed rack, not shown, on which the music sheets M are hung in position to be drawn across the table to the spools. The latter, only one of which is shown, marked 60 N in Figure 1, are received in holders mounted on a vertical front board A² adjacent the table top. Each consists of a bracket D having a hollow head D' in which is mounted a bar or slide D² having its outer end rounded to match to a corresponding recess, not shown, in one end of the spool, and its inner end abutting against a helical spring D³ within the head. A pin D⁴ extending radially from the slide is received in a longitudinal slot d in the head and serves to limit the axial movement of the slide and prevent its withdrawal. 65

In the head D' opposite to the slide, is fixed a stud D⁵ having a head D⁶, on which 75 is mounted a sprocket-wheel D⁷ having on its outer face a bridge D⁸ extending over the head D⁶ of the stud and equipped with a transverse rib D⁹ adapted to engage in the usual notch or slit, not shown, in the opposite end of a spool N.

The spools are inserted by engaging the rounded slide D² in one end and by forcing the slide inwardly against its spring, engaging the slit at the other end of the spool 85 with the rib D⁹ of the next bracket D, and the brackets are so disposed relatively to each other and to the sheet-channels on the plate B, as to present the spools in exact alignment with such channels and sheets. 90

The spools are rotated in the direction to wind the sheets thereon by sprocket chains F' running on the sprocket-wheels D⁷ from sprocket-wheels F² loosely mounted on a shaft F extending along the front of the 95 apparatus and supported in bearings A³ on a shelf A⁴ below the level of the table. Each sprocket-wheel F² is held between collars F³ F⁴ fixed on the shaft, and the collar F³ carries ratchet teeth F⁵ engaged by a pawl F⁶ 100 on the sprocket-wheel F² held in yielding engagement by a spring F⁷.

The shaft F is revolved by a belt, not shown, running on a pulley F³ from any suitable motor, not shown, controlled by the operator.

- 5 The sheets lie in the channels on the plate B and are attached at their ends to the cores of the spools by the attendant; the ratchet and pawl permits the operator to rotate the spools independently by hand in the winding direction for the required number of turns to insure frictional engagement, and the shaft F is then rotated, imparting motion through the sprocket-wheels and chains to the spools, thus drawing the sheets from 10 the table, exposing them for inspection during their traverse across the plate B on which they are guided by the ribs B', and winding them smoothly upon the spools.

By forming the table top of the metal 20 plate B, a plane smooth surface is obtained capable of withstanding the wear of the sheets, and not liable to become warped or otherwise changed by atmospheric conditions of heat and moisture.

25 G is a shaft mounted in uprights A¹⁰ above the table at the rear, driven by a belt E from a pulley E' on the shaft F to a pulley E². The shaft G carries a series of depending links G' in which is mounted a shaft G² provided with cylindrical brushes G³ located to match each to a sheet in its traverse from the rack to the table top. The brush shaft G² is rotated by a sprocket chain G⁴ at one end, running on sprocket-wheels on the 30 shafts G and G².

35 The shaft G² with the links G' forms a suspended frame which may be swung to bring the brushes G³ into wiping contact with the surface of the sheets and thus loosen and brush away any disks of paper not wholly detached or removed in the perforating process, or other shreds of paper or other foreign matter adhering to the surface of the sheet. The brushes are 40 swung into and out of such contact by the attendant through any suitable means.

On the front edge of the table is a series 45 of strips or members H, over which the sheets pass in their traverse from the table to the spools. Each member is hollow, having a narrow slit or mouth, not shown, extending along its upper edge, adapted by means of a partial vacuum in its interior to cause any particles of dust or shreds of paper in the perforations of the sheet to be drawn therefrom by suction and thus free the sheet from matter liable to enter the tracker-board apertures of a playing mechanism with which the sheet is to serve.

50 J is a shaft extending longitudinally beneath the table and suspended from the latter by hangers A''. It carries a lever of bell crank form, the horizontal arm of which 55 carries a horizontally disposed rod on which are pivoted the lower ends of vertical rods

J² extending through the table A and plate B between adjacent pairs of ribs B', and each carries at its upper end a yoke J³ equipped with a pair of separated horizontal transverse rollers J⁴ serving as antifriction guides for a bar L loosely mounted in the yokes and arranged to be reciprocated by hand longitudinally of the table and above the latter.

55 In the bar L and over each sheet-channel is loosely mounted a short vertical shaft or pintle L' held to the bar by collars L² above and below the bar, and free to rotate in the latter while moving therewith. Each pintle carries at the lower end a bifurcated radial 60 arm L³ in which is mounted a circular disk or wheel.

65 The wheels L⁴ of the series, on each side of the centre, are provided with inking rollers L⁵ mounted on the arm L³, and are adapted to print each an expression line on the sheet passing beneath it when lowered thereon. The central wheel L⁶ of the series is shown as not equipped with an ink roller and is intended to be guided along the expression 90 line on the central master-sheet and thus cause the printing wheels L⁴ to produce corresponding lines on their sheets.

70 The bar L and its wheels and rollers are held suspended above the table during the introduction of the sheets and are lowered during the winding operation. These rising and sinking movements are effected through one of the levers which is connected through a rod J⁵ to a foot lever J⁶ pivotally mounted 95 in a portion A¹² of the frame at the mid-length of the apparatus. By depressing the outer end of the foot lever the rods J² and their connections will be raised, and on releasing the foot lever, will be lowered by 100 gravity.

To permit the series of wheels L⁴ and L⁶ to descend, the outer end of the foot lever K² is depressed and the rods J² and their equipment sink by gravity until supported by the wheels L⁴ and L⁶ upon the sheets. The attendant then grasps the bar L and moves it in the yokes J³ to cause the central wheel L⁶ to follow the expression line on the master sheet as the latter traverses across the table, and in doing so causes the printing wheel L⁴ to describe similar paths on the other sheets and print corresponding lines thereon. The bar L and its connections are then raised by depressing the foot lever J⁶ and held in the elevated position 115 until again lowered.

120 S S are idle sprocket-wheels mounted on the board A² and engaging the sprocket chains F¹ to induce the desired tension in the latter by taking up any slack.

125 Modifications may be made in the forms and proportions of the mechanisms without departing from the principle of the invention, and parts may be used without the 130

whole. The apparatus may be constructed to treat a greater or less number of sheets than here shown.

I claim:

5 1. In an apparatus of the character set forth, a series of spool holders in axial alinement, each arranged to receive a spool, a shaft, means for driving the same, means for rotating simultaneously a plurality of
10 spools and guiding sheets thereto, means for permitting of turning any of such spools in advance independently of the others in initiating the winding operation, and suction means for freeing the sheets from dust
15 during their passage through the apparatus.

2. In an apparatus of the character set forth, a series of spooling devices, each comprising a head, a yielding slide in one end 20 of said head adapted to engage one end of a spool, a sprocket-wheel loosely mounted at the opposite end of said head having means for positively engaging the opposite end of an adjacent spool, a shaft, a series of
25 sprocket-wheels on said shaft, and sprocket chains running on said sprocket-wheels.

3. The spooling device described, comprising a head having means for engaging the adjacent ends of two adjacent spools,
30 a driven sprocket-wheel for rotating one

of said spools, a shaft, a clutch connecting said shaft to said driving sprocket-wheel, and a sprocket chain running on said sprocket-wheels.

4. The spooling device described, comprising a head having means for engaging the adjacent ends of two adjacent spools, a driven sprocket-wheel for rotating one of said spools, a shaft, a driving sprocket-wheel loosely mounted on said shaft, a 35 ratchet wheel fixed on said shaft, a pawl on said driving-sprocket-wheel, in engagement with said ratchet wheel, and a sprocket chain running on said sprocket-wheels.

5. In an apparatus of the character set forth, a series of spooling devices, each comprising a head, a yielding slide in one end of said head adapted to engage one end of a spool, a sprocket-wheel loosely mounted at the opposite end of said head having 45 means for positively engaging the opposite end of an adjacent spool, a shaft, a series of sprocket-wheels on said shaft, sprocket chains running on said sprocket-wheels, and means whereby such spools are rotatable independently in the winding direction.

In testimony that I claim the invention above set forth I affix my signature.

NUNEZ CLARENCE FERRIS.
